Primary Examiner—Wallace R. Burke*Assistant Examiner*—Melody Brown*Attorney, Agent, or Firm*—Fay, Sharpe, Beall, Fagan, Minnich & McKee**[57]****CLAIM**

The ornamental design for an automobile fender skirt, as shown and described.

DESCRIPTION

FIG. 1 is a front elevational view of an automobile fender skirt showing my new design;

FIG. 2 is a side elevational view thereof;

FIG. 3 is a side elevational view thereof;

FIG. 4 is an opposite side elevational view thereof;

FIG. 5 is a rear elevational view thereof; and,

FIG. 6 is a bottom plan view thereof.

The broken lines shown in FIGS. 1, 2, 3, 5 and 6 showing the associate automobile and the flange of the automobile fender skirt is for illustrative purposes only and forms no part of the claimed design.

FIG. 3

FIG. 4

FIG. 2

FIG. 1

FIG. 5

FIG. 6
